UNITED STATES PATENT OFFICE

159,293

CONTAINER FOR SHAVING IMPLEMENTS OR THE LIKE

Carl Otto, New York, N. Y., assignor to Eversharp,
Inc., Chicago, Ill., a corporation of Delaware

Application November 23, 1948, Serial No. 149,783

Term of patent 14 years

(Cl. D58—11)

To all whom it may concern:

Be it known that I, Carl Otto, a citizen of the United States, residing at New York, in the county of New York and State of New York, have invented a new, original, and ornamental Design for a Container for Shaving Implements or the like, of which the following is a specification, reference being had to the accompanying drawing, forming a part hereof.

In the drawing:

Fig. 1 is a front elevational view of a container for shaving implements or the like, showing my new design;

Fig. 2 is a side elevational view thereof;

Fig. 3 is a front elevational view showing the top and bottom portions of the container separated;

Fig. 4 is a top plan view of the lower portion of the container taken on the line 4—4 of Fig. 3; and

Fig. 5 is a perspective view, on reduced scale, showing the back of the container.

The dotted lines shown in the drawing are for illustrative purposes only.

I claim:

The ornamental design for a container for shaving implements or the like, substantially as shown and described.

CARL OTTO.
